GERMANY

PACKING CONTAINER

Application filed June 28, 1928, Serial No. 288,884, and in Germany July 8, 1927.

The packing containers for liquid or powdery chemical products designed to be sent to tropical countries, i. e. exposed for longer time to heat and to the action of sea water, 5 have hitherto been made from sheet metal, although containers of this material do not thoroughly fulfill the requirements. Such containers must not only be perfectly watertight and airtight but also capable to withstand the 10 corroding action of liquid or powdery chemicals which have become moist. The sheet metal boxes or containers have bottom plates soldered in the body and this soldering point is specially liable to suffer from 15 the action of the corroding contents.

It has been proposed to use, as material for such containers, a specially prepared cardboard which withstands the action of chemicals, specially if the outer surface of the container 20 is coated with varnish or the like. The difficulty connected with such cardboard containers consists in the obtention of a watertight and airtight closing, as it is impossible to provide in the cardboard a lasting thread, 25 so that tightly closing screw stoppers cannot be used.

At this point intervenes the invention. The invention starts also from the use of cardboard for the body of the container and for 30 the lid, but provides a metal armature for the lid which forms a charging opening with threaded neck, so that the container can be closed by a screw lid of metal.

With this object in view, a ring of sheet 35 metal is arranged in the ring-shaped cardboard lid, this sheet metal ring having an upwardly bent outer edge, the cardboard lid having a double flange with which the upwardly bent edge of the sheet metal ring engages. For re-inforcing the lid has further a 40 ring-shaped lower layer of cardboard the upwardly bent edge of which is rabbeted together with the flange of the sheet metal ring. Into the threaded neck formed by the inner 45 edge of the sheet metal ring a cup is placed, with interposition of a rubber packing, so that the flange of said cup bears on the end face of the threaded neck, whereupon a screw cap is forced over the threaded neck.

50 An embodiment of the invention is illus-

trated by way of example, in the accompanying drawing, in which:

Fig. 1 shows the container in radial section.

Fig. 2 is a top plan view of Fig. 1.

Fig. 3 is a part section through the closure 55 of the packing container on larger scale.

The body *a* of the container is enclosed by a casing *b* the lower edge *c* of which is folded inward and upward so that the downwardly directed flange *h'* of the bottom plate *h* engages between the two arms of this folded edge *c*. These elements are made of cardboard and they have on the inner surface a coating *m* of a suitable varnish. The upper edge of the casing *b* does not extend to the top 60 edge of the body *a* and forms a shoulder for the edge of the lid of cardboard.

The packing container as just described is known per se. The novelty consists in the construction of the lid. This lid of cardboard has a double edge *d*, *d'* the outer longer arm *d'* of which bears on the upper edge of the casing *b*. Between the two arms *d*, *d'* of the edge of the lid the upwardly bent outer edge *e'* of a ring-shaped plate *e* of sheet metal 75 engages the inner upwardly turned edge *f* of which forms a threaded neck serving as charging hole for the container. Under the sheet metal plate *e* a ring *g* of cardboard is arranged which has an outer upwardly turned 80 edge *g'* which, together with the edge *e'* of the sheet metal ring *e*, is clamped between the two arms *d*, *d'* of the cardboard lid. To further unite the sheet metal ring *e* with the lower re-inforcing ring *g* of cardboard, 85 pointed flaps *k* are stamped out of the sheet metal ring *e* and bent downwardly and pressed into the cardboard ring *g*. The inner upper edge *f'* of the threaded neck *f* is bent inward and then downward again, and a cup *r* having a horizontal flange *r'* is pressed, with interposition of a rubber ring *n* or of any other suitable packing, into said flange *r'*. The threaded neck *f* and the cup *r* are closed 90 by a screw cap *s* screwed onto the outer surface of the threaded neck *f* and having handles *p*. The re-inforcing ring *g* of cardboard has also a coating of varnish *m'* on the lower 95 surface.

We claim:—

1. A packing container, comprising in combination, a card board lid, the inner edge of which is folded over, a sheet metal ring having an upwardly bent outer edge engaging between the folded inner edge of said lid, an inner upwardly bent flange on said ring, which flange is threaded to form a screw neck, the upper edge of said inner bent flange being bent horizontally and then downwardly, and a screw cap threaded on said screw neck.

15 2. A water and air tight packing container formed of card board for carrying liquid or powdery chemical substances comprising, in combination, a card board lid, a metal ring having a threaded neck thereon, a closure adapted to be threaded on said neck, and a ring shaped insert of card board for supporting said ring, the said insert having an upwardly turned outer flange engaging between said ring and said lid.

25 3. A water and air tight packing container of card board for liquid and powdery chemical substances, comprising the combination of a card board lid having a downwardly and inwardly folded edge thereon, a metal ring having a threaded neck thereon, as well as an upwardly bent annular flange on the 30 outer periphery thereof, a closure threaded on said neck, a ring shaped insert of card-board supporting said ring, the said insert having an upwardly turned outer flange engaging between said ring and said lid, the 35 said flange being held, together with said upwardly bent inner flange of said ring, by means of the downwardly folded edge of said lid.

40 4. A water and air tight packing container of card board for liquid or powdery chemical substances comprising the combination of a card board lid having a downwardly folded edge thereon, a sheet metal ring having a threaded neck thereon, as well as an upward- 45 ly bent annular flange on the outer periphery thereof, a closure threaded on said neck, a ring shaped insert of card board supporting said sheet metal ring and having an upwardly turned outer flange engaging between said 50 ring and said lid, the said flange of said insert being held, together with the flange of the ring, by means of the downwardly folded edge of the lid, and flaps stamped out of the lateral portion of said sheet metal ring and 55 engaging with the flange of said card board insert.

5. A packing container comprising, in combination, a card board lid the inner edge of which is folded inwardly and downwardly 50 upon itself, a sheet metal ring having an upwardly bent outer flange engaging between the folded inner edge of said lid, and an inner upwardly bent flange on said ring, which flange is threaded to form a screw neck, the 55 upper edge of said inner bent flange being

bent horizontally and then downwardly, a packing ring on the downwardly directed end of said screw neck, a metal cup pressed into said screw neck, and a screw cap threaded on said screw neck.

In testimony whereof we affix our signatures.

GEORG STABERNACK.
